TELEVISION CAMERA

Orville W. Larson, Elmhurst, Ill., assignor to Ampex
Corporation, Redwood, City, Calif.

Filed Sept. 9, 1970, Ser. No. 24,895

Term of patent 14 years

Int. Cl. D14—03

U.S. Cl. D61—1

FIG. 1 is a perspective view of the front, top and right side of a television camera, showing my new design; and

FIG. 2 is a perspective view of the rear, bottom and left side of the camera of FIG. 1.

I claim:

The ornamental design for a television camera, substantially as shown.
